DESIGN FOR A CARRYING BAG

William L. M. Clark, St. Louis, Mo., assignor to W. L. M. Clark, Inc., St. Louis, Mo., a corporation of Missouri

Application October 12, 1942, Serial No. 108,506

Term of patent 14 years

To all whom it may concern:

Be it known that I, William L. M. Clark, a citizen of the United States, residing in the city of St. Louis and State of Missouri, have invented a new, original, and ornamental Design for a Carrying Bag, of which the following is a specification, reference being had to the accompanying drawing, forming part thereof.

Fig. 1 is a perspective view of a carrying bag showing my design in a slightly opened position.

Fig. 2 is a perspective view of the bag in Fig. 1 in its extended position; and Fig. 3 is a side elevational view thereof.

I claim:

The ornamental design for a carrying bag, substantially as shown.

WILLIAM L. M. CLARK.
